(57) **CLAIM**

The design for a dynamic diffusor, as shown and described.

DESCRIPTION

FIG. 1 is a top plan view of a dynamic diffusor in accordance with my design;

FIG. 2 is a top, front perspective view thereof;

FIG. 3 is a bottom plan view thereof;

FIG. 4 is a bottom, rear perspective view thereof;

FIG. 5 is an elevational view thereof; and,

FIG. 6 is a cross-sectional view taken through FIG. 5 which

shows the depth of the outer contours of the design.
